UNITED STATES PATENT OFFICE

NEIL B. WOLCOTT, OF WASHINGTON, DISTRICT OF COLUMBIA, ASSIGNOR TO THERMO-
ICE CORPORATION, OF AUBURN, NEW YORK

REFRIGERATING APPARATUS

Application filed February 8, 1927. Serial No. 166,662.

This invention relates to refrigerating apparatus of the still-condenser-absorber type and has for its object to improve and simplify apparatus for artificial refrigeration, and especially the means employed for distilling the gas—ammonia, for example—from the strong liquor and for absorbing the expanded gas after refrigeration into the weak liquor; also, to render such apparatus more efficient and rapid in operation and more economical.

A further object of the invention resides in the production of a refrigerating apparatus of the type specified which is extremely compact and comparatively inexpensive in manufacture, and in which the condenser coil also serves as a feed line for the refrigerant thereby reducing the cost of manufacture of the device as well as providing increased efficiency in operation as will later appear.

20 A further object of the invention consists in the provision of a novel type of diffuser which facilitates absorption of the expanded gases by the weak liquor after refrigeration has taken place.

25 Other objects of the invention together with their attendant advantages will be apparent from the following description when taken in connection with the accompanying drawing; in which

30 Figure 1 is a vertical section through the complete apparatus; and

Figure 2 is a plan view of the diffuser with the major portion of the apparatus removed for the purpose of better disclosing the construction.

As hereinbefore stated one of the essential features of the present invention resides in the provision of a comparatively simple and inexpensive refrigerating apparatus of the 40 still-condenser-absorber type and to this end the apparatus is formed in a unitary construction. The numeral 1 indicates a tank or receptacle closed at the top and bottom and provided with three horizontally disposed partitions 2, 3 and 4. The tank is preferably, although not necessarily, of cylindrical form and the partitions 2, 3 and 4 are of the same shape and are welded or otherwise connected to the inner wall of the tank 1. The partitions divide the receptacle into four compart-

ments 5, 6, 7 and 8, the upper compartment serving as a combined still and absorber, the next lower compartment 6 serving as a heating chamber, the compartment 7 being adapted to serve as a condenser, and the lowest compartment 8 as a receiver for the condensed gases.

Connected into the top of the still compartment 5 is a gas pipe 9 preferably provided with a gage 9' and with a check valve 10 although a manually operated valve may be used in lieu of the check valve if found desirable. Leading downwardly from the pipe 9 is a pipe 11 which extends into the condenser compartment 7 and is formed into a flat coil 12 which leads thence as indicated by numeral 13 into the receiver compartment 8. A heater 14 is placed in the compartment 6 for operating the still or generator 5 and while the heater shown is of the coal oil type it will be understood that a gas heater or any other conventional form of heater may be substituted therefor if found desirable.

Disposed adjacent the bottom of the still or generator 5 is a plate 15 preferably circular in outline and of substantially the same area as the bottom of the generator. This plate is provided with a plurality of minute perforations 16 for the passage of the spent gases returning from the refrigerating coil through the pipe 17 when the valve 17' is open. It will be readily understood by those skilled in the art that the minute perforations 16 in the plate 15 will cause the returning gases to be broken up into very small bubbles which will the more readily be absorbed by the spent liquor in the still. Furthermore, the stream of small bubbles passing upwardly in the central portions of the generator 5 will set up a circulation whereby the hot liquid at the bottom of the generator will move upwardly while the cooler liquid at the top of the generator will move downwardly along the sides thereof and thus be in a position to more readily absorb the spent gases entering through the pipe 17.

By reason of this circulation of the liquid about the point of ingress of the gas the efficiency of the generator is greatly increased.

In the ordinary operation of the generator

it will be obvious that the ammonia gas will assume a position at the top of the compartment 5, then a layer of steam just below, and finally the liquor at the bottom of the still.

- 5 Under a very rapid heating or distillation of the contents of the generator 5 there is ordinarily the liability of a small portion of the steam forcing its way through the layer of ammonia gas at the top of the still and passing into the pipe 9. For the purpose of avoiding this contingency a plate 18 preferably circular in outline is attached by straps 19 to the top of the still 5, and is spaced slightly below the entrance to the pipe 9 thereby serving to prevent the escape of steam into this pipe should there be a tendency in this direction due to the too rapid heating of the contents of the still.

A cooling circuit 20 provided with valves 20 21 and 22 leads through the generator 5 and is provided with a coil 23 located in this generator; the coil continuing from the generator through pipe 24 to a waste pipe 25. The latter pipe also serves as a waste connection for the 25 condenser compartment 7, entrance to which is controlled by the valve 21 in the cooling circuit above referred to.

Attached to the pipe 11 above the coil 12 is a pipe 26 provided with a manually operated 30 valve 27. This pipe 26 forms a part of the feed line for carrying the refrigerant to the refrigerating coil; the other part of the feed line consisting of the coil 12 of the condenser and the pipe 13 which carries the condensate 35 into the receiver 8. The operation of this part of the device will be described in connection with the operation of the complete apparatus.

In the operation of the device a partial vacuum is formed in the generator 5 by applying 40 a pump to an elbow (not shown) in the pipe 9. The heater 14 is then set in operation and the gases are then distilled over through the pipe 9 when sufficient pressure is reached within the generator; the gases passing through pipe 45 9 to pipe 11 and the coil 12 where they are condensed, due to the passage of cooling water around this coil, the valve 21 having been previously opened for this purpose. During this operation the valve 22, of course, is closed.

50 When the distilling operation is completed and it is desired to pass the refrigerant through the refrigerating coil (not shown) the valve 21 remains open so as to pass cooling water around the coil 12 and the valve 27 55 is opened, thereby forming a feed line to the refrigerating coil consisting of the pipe 13, coil 12, pipe 11, and pipe 26. By this operation it will be apparent that the refrigerant leaving the receiver 8 is further cooled on its way to the refrigerating coil. This further lowering of the temperature of the refrigerant which is being fed out for the purpose of refrigeration allows of a greater 60 expansion of liquid when reaching the point

of refrigeration thereby causing a much greater efficiency in the operation of the device.

After the refrigerant has served its purpose the valve 17' is opened and the expanded gases are returned through pipe 17 into the compartment 5 which now serves as an absorber. The gases being broken up in passing through the apertures 16 will therefore be readily absorbed by the spent liquor within the absorber 5. It will be understood by those 70 familiar with this type of apparatus that before the spent gases are returned to the absorber 5 the spent liquor contained within the absorber is cooled by means of water passing through the coil 23, the latter being placed 75 in communication with the cooling circuit by opening the valve 22. When the gases are reabsorbed within the liquor contained within the still-absorber 5 the process just described 80 may be repeated.

85 From the foregoing description taken in connection with the accompanying drawings it will be apparent that I have devised an extremely simple and inexpensive refrigerating apparatus which comprises a unitary 90 structure formed from a single tank divided by partitions to provide the several necessary elements and it will be further apparent that the efficiency of the apparatus is greatly increased through the fact that the condenser 95 coil also serves as a part of the feed line for carrying the refrigerant to the refrigerating coil; this construction serving to further lower the temperature of the refrigerant and thereby providing greater heat absorbing 100 powers for the latter when passing through the refrigerating coil.

105 In accordance with the patent statutes I have described what I now believe to be the best embodiment of the invention, but I do not wish to be understood thereby as limiting myself or the scope of the invention, as many changes and modifications may be made without departing from the spirit of the invention; all such I aim to include in the scope 110 of the appended claims.

115 What I claim as new and desire to secure by Letters Patent is:

1. A refrigerating apparatus including a cylindrical receptacle constructed and arranged to provide an upper generator compartment, a lower condenser compartment and a receiver compartment, a gas pipe leading from the top of the generator and formed into a coil in the condenser compartment and leading thence to the receiver compartment.

120 2. A refrigerating apparatus including a single receptacle constructed and arranged to provide a generator compartment, a condenser compartment and a receiver compartment, a gas pipe leading from the top of the generator compartment downwardly and inwardly and formed into a coil in the condenser compartment, said coil terminating in a pipe leading into the receiver compartment. 125 130

5 3. A refrigerating apparatus including a cylindrical receptacle constructed and arranged to provide an upper generator compartment, a lower condenser compartment and a receiver compartment, a gas pipe leading from the top of said generator compartment and formed into a coil in the condenser compartment and leading thence to the receiver, and valved water cooling circuits leading through said generator and said condenser.

10 4. A refrigerating apparatus including a generator, a condenser and a receiver, water cooling circuits leading through said generator and condenser, a gas pipe leading from said generator and formed into a coil in the condenser and leading thence to the receiver, and a valved feed line tapped to said gas pipe between its connection with the generator and the coil, whereby the coil may serve as a part of the feed line from the receiver to a refrigerating coil.

15 5. A refrigerating apparatus including a cylindrical receptacle divided into three vertically arranged compartments, means within the top compartment to provide an absorber, means within another compartment to provide a condenser, said third compartment serving as a receiver.

20 6. A refrigerating apparatus including a cylindrical receptacle, a plurality of partitions in said cylindrical receptacle to form vertically arranged compartments, means associated with the top compartment to provide a still or generator, means associated with another compartment to provide a condenser, said third compartment serving as a receiver.

25 7. A refrigerating apparatus including a cylindrical receptacle, a plurality of partitions in said cylindrical receptacle to form vertically arranged compartments, means associated with the top compartment to provide a generator, means associated with another compartment to provide a condenser, a heating apparatus associated with a third compartment, and another compartment serving as a receiver.

30 8. In a refrigerating apparatus of the class described, a generator, a pipe having its discharge end disposed adjacent the bottom of the generator for returning spent gases thereto, a perforated diffuser plate disposed above said pipe so as to cause a circulation of the gases upwardly in the center portions of the generator and downwardly along the sides thereof, said plate being substantially flat at its central portion and having a continuous downturned flange at its edge.

35 60 NEIL B. WOLCOTT.
